[57] CLAIM

The ornamental design for a flashlight, as shown and described.

DESCRIPTION

FIG. 1 is a bottom, front perspective view of the flashlight showing my new design;

FIG. 2 is a bottom rear perspective view thereof;

FIG. 3 is a front elevational view thereof;

The flashlight is cylindrical in cross-section.

The top and opposite side of the flashlight are identical to the bottom and side as shown in FIGS. 1 and 2.
